US00D828010S

(12) **United States Design Patent** (10) Patent No.: **US D828,010 S**
(45) Date of Patent: **** Sep. 11, 2018**

(54) **HANDHELD ROLLER DEVICE FOR SEWING**

(71) Applicant: **CLOVER MFG. CO., LTD.**,
Osaka-shi, Osaka (JP)

(72) Inventors: **Joan Hawley**, Westerville, OH (US);
Yasuhiro Fujiwara, Osaka (JP); **Yui Teramoto**, Osaka (JP)

(73) Assignee: **CLOVER MFG. CO., LTD.**, Osaka (JP)

(**) Term: **15 Years**

(21) Appl. No.: **29/596,640**

(22) Filed: **Mar. 9, 2017**

(30) **Foreign Application Priority Data**

Mueller & Larson, P.C.

(57) **CLAIM**

We claim the ornamental designs for a handheld roller device for sewing, as shown and described.

DESCRIPTION

FIG. 1 is a perspective view of a handheld roller device for sewing according to my design;

FIG. 2 is a front elevational view thereof, the undisclosed rear being identical;

FIG. 3 is a top plan view thereof;

FIG. 4 is a bottom plan view thereof;

FIG. 5 is a left side elevational view thereof;

FIG. 6 is a right side elevational view thereof;

FIG. 7 is a sectional view taken along lines 7-7 FIG. 3;

FIG. 8 is a sectional view taken along line 8-8 of FIG. 2; and,

FIG. 9 is a sectional view taken along line 9-9 of FIG. 2.

1 Claim, 6 Drawing Sheets
